RAILROAD RAIL SPLICE BAR

Filed July 7, 1927

Inventor
Erwin Griesbaum
By Cornwall, Bedell, Janus, ^{and} _{attys.}

UNITED STATES PATENT OFFICE.

ERWIN GRIESBAUM, OF ST. LOUIS, MISSOURI.

RAILROAD-RAIL SPLICE BAR.

Application filed July 7, 1927. Serial No. 203,983.

This invention relates to new and useful improvements in railroad track construction and more particularly to a splice bar for the rails.

5 The main objects of the invention are to provide simple and inexpensive means which will securely tie together the abutting ends of the rails and which is so constructed as to allow a certain amount of play for said 10 rail ends without affecting said means.

Other objects of the invention are the provision of a splicing connection for the abutting ends of the rails, said splicing connection having a three point engagement 15 with said rails so disposed as to provide a sufficient degree of flexibility between said rails and said splice bar for railroad rails, said bar having a single point engagement with the ball portions of the abutting rails 20 and having a plurality of points of engagement with the base flanges of said rails, thereby permitting slight yielding movement 25 of the parts relatively to each other and preventing excessive wear of the ball engaging portions of said splice bar.

Further objects of the invention are to provide a splicing connection for rails, whereby by the particular construction of 30 said splicing connection a three point engagement in all planes is effected between said connection and the abutting rails. Thus the rails are held firmly together in all the planes, but have sufficient flexibility to allow lateral parallel motion of said rails.

35 Additional objects of the invention are the provision of an improved splice bar of the class described which is of simple construction and can be economically manufactured, can be readily secured in position, and which 40 is adapted to be wedged between the opposed faces of the rail by use of suitable fastening devices, such as bolts and nuts. Preferably a plurality of such fastening devices are used and they are disposed within a defined area 45 so that one of the bolts will be sufficient to hold the joint together as a unit.

With these and other objects in view my invention consists of certain novel features and arrangements of parts hereinafter more 50 fully described, claimed and illustrated in the accompanying drawings in which—

Figure 1 is a top plan view of a pair of splice bars and showing the rails in dot-and-dash lines.

Figure 2 is a side elevational view of 55 same.

Figure 3 is an end view.

Figure 4 is a transverse vertical cross section taken centrally through a modified form of my invention. 60

Referring by numerals to the accompanying drawing 10 designates a splice bar which is arranged on each side of the abutting ends of adjacent rails A, which are of usual construction, having a ball portion 12, a web 14 65 and a flange base 15.

The splice bar 10 is in the form of an elongated plate of suitable thickness to provide the necessary strength and rigidity. The lower edge 16 of the bar is spaced from 70 the upper face 15^a of flange 15 and is provided at each end with a depending extension 16^a, the lower face of each of which is inclined from horizontal and is adapted to bear against the face 15^a. 75

The upper edge 17 of said bar is spaced a suitable distance from the underside 12^a of the ball portion 12 and is tapered downwardly near its ends 18 as indicated at 17^a. Centrally disposed on the upper edge 17 and 80 projecting upwardly and laterally therefrom is a lug 19 having a curved end 19^a which is adapted to bear against the curved surface formed by the junction of the underside 12^a with the web 14. Lug 19 is of suitable width 85 so as to provide the proper bearing surface between the rail ends and said lug. The underside 12^a of ball portion 12 and the upper face 15^a of flange 15 are inclined from horizontal and converge toward the web 14, 90 thereby forming tapering seats for the reception of extensions 16^a and 19 so that, when bar 10 is drawn towards the web 14, 95 said extensions are wedged against the respective surfaces and form a secure joint in said bars 10 and receive nuts 21 by means 100 of which said bars may be clamped against said web. Preferably two bolts 20 are used, the bolt apertures being disposed equi-distant from the vertical center of the bar and are arranged within the triangle formed by 105 lines drawn between the points of interengagement of said splice bar with the rails.

The arrangement of a single point of en-

gagement between the splice bar and the abutting ends of the adjacent rails insures flexibility of the rail joint and at the same time provides a strong and secure splicing connection and prevents undue wear of the splice bar.

In Figures 1 to 3 is shown the preferred form of my invention. However, where an extra degree of strength is required a splice bar of the modified form as shown in Figure 4 could be used. In this form the body portions 22 are spaced a suitable distance from the web portion of the rail and the downward extensions 22^a are arranged at an angle to the body portion, while the upward extensions 22^b are considerably lengthened to bring them against the webs of the rails. The top and bottom edges of body portions 22 are disposed angularly relative thereto as indicated at 23 and 24 respectively, thereby forming said splice channel shaped in cross section, which greatly strengthens the splice bar.

A rail joint formed by the use of my improved splice bars provides an efficient connection between the adjacent rails, is flexible to a sufficient degree to allow a certain amount of play of the rails relatively to each other and to said splice bars.

My improved splice bar can be economically manufactured, contains but few parts and can be readily attached in position.

While I have shown and described the preferred forms of my invention, obviously various minor changes can be made in the construction and size of my splice bar, without departing from the spirit of my invention.

I claim:

1. A splice bar for railway rails comprising a single piece member having an elongated body portion adapted to be spaced throughout its entire length from the web portions of the abutting rails, said body portion being provided at its lower edge at each end with a projecting lug having an inclined face for engaging the upper face of the rail flange intermediate the edge thereof and the web portion of the rail, the upper edge of said body portion being provided with a laterally and centrally disposed lug for engaging the under sides of the ball portions of the abutting rails, thereby forming a three point engagement between said splice bar and the rails.

2. A three point splice bar for railway rails comprising a single piece member having an elongated body portion provided at its lower edge at each end thereof with a downwardly presented lug adapted to engage the upper face of the flange of each rail at a point spaced from the edge of said flange and the web portion of the rail, said body portion being provided at its upper edge with a centrally disposed single lug

extending laterally therefrom and engaging the underside of the ball portions of the abutting rails, thereby providing a three point engagement between the rails of said splice bar, and means for placing said body portion under compression, said means being in engagement with said body portion within the triangular area defined by the lines connecting said three points of engagement.

3. A splice bar for railway rails comprising a body portion provided at its lower edge near its ends with inwardly extending portions adapted to bear against the upper faces of the flanges of the abutting rails, said splice bar having its upper edge provided with an inwardly extending portion spaced intermediate of said lower portions and adapted to bear against the undersides of the ball portions of said rails thereby forming a three point engagement between said splice bar and said rails.

4. In a railway splice joint, the combination with two abutting rails, of an elongated splice bar arranged on each side of the abutting ends of said rails and spaced therefrom throughout its entire length, each splice bar being provided at each end with a downwardly projecting lug engaging the upper face of each rail flange at a point spaced from the edge of said flange and from the web portion of said rail, each splice bar being provided with a lug formed on its upper edge equidistant from the ends thereof and projecting laterally to engage the undersides of the ball portions at their junction with the web portions of the rails whereby each splice bar has a three point engagement with the abutting rails both in vertical and horizontal planes.

5. A splice bar for railroad rails comprising an elongated member adapted to be placed parallel with the webs of the abutting rails, the edges of said member being spaced from the horizontal portions of said rails, the lower edge of said member being provided with a plurality of inward extensions having inclined faces adapted to engage the inclined upper faces of the rail flanges and the upper edge of said member having a centrally disposed inward extension adapted to engage the inclined faces of the ball portions of said rails.

6. A splice bar for railway rails comprising an elongated member adapted to be placed parallel with the webs of the abutting rails and having its edges spaced from the horizontal portions thereof, and oppositely disposed extensions formed integrally with the edges of said member and extending inwardly therefrom, said extensions being adapted to bear against the oppositely inclined surfaces of the horizontally disposed portions of said rails for flexibly and securely joining said rails.

7. In a railway splice joint, the combina-

tion with two abutting rails, of an elongated splice bar arranged on each side of the abutting ends of said rails and spaced therefrom throughout its entire length, each splice bar being provided at each end with a downwardly projecting lug engaging the upper face of each rail flange at a point spaced from the edge of said flange and from the web portion of said rail, each splice bar being provided with a lug formed on its upper edge equidistant from the ends thereof and projecting laterally to engage the undersides of the ball portions at their junction with the web portions of the rails whereby each splice bar has a three point engagement with the abutting rails both in vertical and horizontal planes, and securing means extending freely through the web portions of said rails and seated in the body portions of said splice bars at points disposed within the triangular areas defined by lines drawn between the points of engagement of said splice bars with said rails.

In testimony whereof I hereunto affix my signature this 2nd day of July, 1927.

ERWIN GRIESBAUM.
